Homest Stand Mixer Cover, Jun. 11, 2019, found on Jan. 28, 2021 at Amazon.com: HOMEST Stand Mixer Cover Compatible with KitchenAid Bowl Lift 5-8 Quart , Dust Cover with Zipper Pocket for Accessories, Red (Patent Design): Kitchen & Dining (Year: 2019).*

Primary Examiner — Karen S Acker

(57) **CLAIM**

The ornamental design for a mixer dust cover, as shown and described.

DESCRIPTION

FIG. 1 is a front perspective view of a mixer dust cover showing my new design;

FIG. 2 is a front view thereof;

FIG. 3 is a rear view thereof;

FIG. 4 is a left view thereof;

FIG. 5 is a right view thereof;

FIG. 6 is a top side view thereof; and,

FIG. 7 is a bottom side view, thereof.

The broken lines depict stitching that forms no part of the claimed design.

1 Claim, 7 Drawing Sheets
